UNITED STATES PATENT OFFICE.

WILLIAM H. PAGE, OF PRESTON, CONNECTICUT.

STEAM-GENERATOR.

SPECIFICATION forming part of Letters Patent No. 331,431, dated December 1, 1885.

Application filed July 30, 1885. Serial No. 173,017. (No model.)

To all whom it may concern:

Be it known that I, WILLIAM H. PAGE, a citizen of the United States, residing at Preston, in the county of New London and State of Connecticut, have invented certain new and useful Improvements in Steam-Generators, of which the following is a specification, reference being had therein to the accompanying drawings.

10 This invention relates to steam-generators for house-heaters; and the novelty consists in the construction, arrangement, and adaptation of parts, as will be more fully hereinafter set forth, and specifically pointed out in the claims.

15 The object of the invention is to provide a boiler which shall be simple and cheap of manufacture, easily and readily constructed for use, and efficient, reliable, and durable in service.

20 To these ends it consists in a boiler made of peculiar sections secured together.

I illustrate the boiler made of two sections, and prefer that construction. With the lower 25 section is formed a complete fire-box, while the upper section has peculiar flues, which, in connection with the masonry, lead the products of combustion to an escape-flue, the arrangement being such as to impart to the water the greatest possible amount of heat from such 30 products. The upper part of the lower casting comprises a peculiar crown-sheet, against which the fierce heat products abut before they circulate through the flues. This crown 35 is made of peculiar form—a double ogee in cross-section—which allows for contraction and expansion. These features and others of importance are illustrated in the accompanying drawings, which form a part of this specification, and in which—

40 Figure 1 is a front elevation of the complete boiler, shown without the necessary masonry, which in practice serves to direct the course of the products of combustion. Fig. 2 is a horizontal section taken on the line $x-x$ of Fig. 1, looking downward. Fig. 3 is a similar view on the line $y-y$ of Fig. 1; Fig. 4, a similar view taken on the line $z-z$ of Fig. 1; Fig. 5, a similar view taken on the line $m-m$, Fig. 1, the same being through the steam-drum. Fig. 6 is a central vertical section

taken on the line $n-n$ of Fig. 1, illustrating the boiler in its relation to the masonry.

For convenience of description, I will describe the construction and operation together.

The lower section, B, is a single casting, which rests on suitable supports, a , built in the masonry A, and the masonry along the sides and back of the boiler is arranged at a 50 distance to provide draft-space A'. The section B comprises an annular water-chamber, b , with corrugated interior b' , which forms the wall of the fire-box and a space, as b'' , which serves as a doorway. It has an annular flange, 55 b^4 , which serves as a securing means or as a bearing for the adjacent section, and its upper horizontal portion comprises a crown-sheet, b^5 , of double-ogee curve in cross-section, this last feature serving to allow for contraction 60 and expansion without cracking. The space above and within the crown-sheet b^5 is connected with the annular water-chamber in the body by a series of vertical water-tubes, b^6 , set at a sufficient distance apart to allow the 65 products of combustion which have been projected against the crown-sheet to be deflected and circulate between them to the space A' between the casting B and the masonry A. Suitable ledges are cast in the part B to support 70 a grate, b^7 .

H designates the upper casting. It comprises a steam-drum, I, having a steam-outlet connection, i , a horizontal water-chamber, J, and a plate, K, having a flange, k , which rests 75 upon and is secured to the flange b^4 of the casting B. The steam-drum I and water-chamber J are connected by a series of five (more or less) vertical parallel tubes, $i' i^2 i^3$, as shown, and the parts J and K are connected 80 by a similar series, $k' k^2 k^3$. These tubes allow the ready circulation of water, and extend parallel from front to rear, the central tubes, i' and k' being necessarily the longest.

The products of combustion which have 85 been projected against the crown-sheet b^5 and deflected between the series of tubes b^6 are forced to pass first down outside of the part b in order to find an escape, by reason of two vertical plates, L L, arranged in the space A' 90 and extending along the length of the tubes b^2 , as seen in Fig. 3. As the said products

have no other escape, they pass under the lower edge, l , of these plates, (see Fig. 6,) and thence upward between said plates L. At the base of the horizontal chamber J is built a closed 5 diaphragm, M, which prevents the products from passing any farther upward, and they pass in a horizontal direction between the parts J and K, and between the central tube, k' , and the adjacent tubes k^2 , as seen in Fig. 3. 10 Passing out at the front side, they are prevented from rising by a horizontal diaphragm, N, and are forced to return on the same horizontal plane between the tubes or legs k^2 and k^3 . (See Fig. 3.) Having passed upward be- 15 tween the plates L L, they now return to the same point, but upon the outside of these plates; hence they pass to the plane above between the parts I and J and across in a horizontal direction between the tubes i^2 and i^3 20 and back between the tubes i' and i^2 , as seen in Fig. 4, to the exit-flue S. (See Fig. 6.) By this construction the products of combustion are forced to pass back and forth in a horizontal direction between the parts J and K 25 and between the parts I and J, as well as be- 30 tween the legs b' , down the outside of the chamber, b, and between and around the several legs i' , i^2 , and i^3 , and k' , k^2 , and k^3 , thus allowing the greater part of the heat to be ab-
sorbed by the water.

A sheet-metal or other proper frame, O, is arranged along the front of the boiler. It is built with reference to the masonry and boiler, and furnishes bearings for the doors, dia- 35 phragm N, &c.

Modifications in details of construction may

be made within wide limits without departing from the principle or sacrificing the advantages of my invention, the essential features of which will be readily understood from the foregoing description, taken in connection with the drawings.

What I claim as new is—

1. In a steam-generator substantially as described, the casting B, formed with a water-chamber which comprises the walls of a fire-box having a double-ogee-curve crown-sheet, as b^5 , and connecting water-ways, as b^6 , all cast in one piece, as set forth. 45

2. The crown-sheet b^5 , having a form of 50 double-ogee curve in cross-section, and having water-connections b^6 , with the casting B, all in one piece of metal, as set forth.

3. The casting B, having water-chamber which forms the walls of the fire-box, a crown-sheet, and a series of water-legs, as b^6 , combined with the plates L, and adapted to serve with masonry, as A. A', as set forth. 55

4. The combination, with the castings H B, as described, of the plates L, and diaphragm M 60 N, as and for the purpose set forth.

5. The casting H, comprising the parts I, J, and K k , connected by water-ways i' and i^2 , &c., $k' k^2$, &c., combined with the casting B 65 b^4 and the plates L, and diaphragms M and N, as and for the purpose set forth.

In testimony whereof I affix my signature in presence of two witnesses.

WILLIAM H. PAGE.
